UNITED STATES PATENT OFFICE.

FRED P. SMITH, OF GLASSBORO, NEW JERSEY.

GAS GOVERNOR.

Application filed January 31, 1923. Serial No. 616,059.

To all whom it may concern:

Be it known that I, FRED P. SMITH, a citizen of the United States, residing at Glassboro, in the county of Gloucester and 5 State of New Jersey, have invented new and useful Improvements in a Gas Governor, of which the following is a specification.

My invention relates to new and useful improvements in a gas governor, and has 10 for its object to improve the construction of devices of this character whereby the valve will be accessible for cleaning and repair purposes.

Another object of the invention is to locate the valve on the outside of the governor body or casing and to enclose the same within a removable cap the latter forming with the governor casing a chamber in communication with the gas inlet and the diaphragm 20 chamber.

Another object of the invention is to so arrange the valve that its opening movement will be opposed to the direction of flow of the gas.

25 A further object of the invention is to provide an improved construction for the safety blow out.

A still further object of my invention is to provide a diaphragm lever of unique construction.

Another object of the invention is to provide a valve structure having new and advantageous features.

With these ends in view, this invention 35 consists in the details of construction and combination of elements hereinafter set forth and then specifically designated by the claims.

In order that those skilled in the art to 40 which this invention appertains, may understand how to make and use the same, I will describe its construction in detail, referring by numerals to the accompanying drawings forming a part of this application, in 45 which:—

Fig. 1 is a vertical longitudinal sectional view of a gas governor embodying my improvements portions of which have been left in elevation.

50 Fig. 2, is a section at the line 2—2 of Fig. 1, with the cap and fluid container removed.

Fig. 3, is a section at the line 3—3 of Fig. 1, with the fluid container removed.

55 Fig. 4, is a bottom plan view of the gas

governor with the cap removed on a slightly reduced scale.

Fig. 5, is an enlarged fragmentary perspective view of the diaphragm lever.

Fig. 6, is an enlarged sectional side elevation of the valve and its stem.

Fig. 7, is an enlarged perspective view of the valve connecting bar.

In carrying out my invention as here embodied, 2 represents the gas governor body 65 or casing including an enlargement forming a portion 4 of the diaphragm chamber communicating with the lever compartment 5 formed in the leg 6 which projects below and beyond one side of the enlargement, said 70 leg having an externally threaded boss 7 intermediate its ends for the reception of the removable cap 8. The boss 7 is so located that for all intents and purposes it produces an extension 9 of the leg 6 which 75 extension is located outside of the boss and is enclosed by the cap 8 when the latter is in place.

Between the enlargement 3 and the boss 7 and preferably at the underside of the leg 6 80 is formed an arm 10 in which is the gas inlet passageway 11 having a channel 12 leading therefrom through the boss 7 to the exterior of the governor housing or casing so as to form a communication between the gas inlet 85 11 and the valve chamber 13 within the cap 8 while on the other side of the leg is formed another arm 14 having an outlet passageway 15 therethrough communicating with the lever compartment and through the latter 90 with the diaphragm chamber. These arms are adapted to be connected in any suitable or well known manner with the service pipes, the supply pipe being connected with the arm 10 and the discharge pipe being connected with the arm 14.

The extension portion 9 of the leg has a hole 16 therethrough to form a communication between the valve chamber 13 and the lever chamber 5 and this hole 16 is surrounded by a valve seat 17 with which coacts the valve 18. The valve 18 comprises a head 19 in the underface of which is embedded a washer 20 preferably of compressible material for engagement with the seat 17. The 105 valve 18 is adjustably mounted upon a stem 21 preferably by being threaded thereon while the valve stem is bifurcated so that parts thereof straddle one end of the valve connecting bar 22 and is pivoted to said 110

connecting bar by a pin 23 or its equivalent. The space between the bifurcated portions of the valve stem is of greater width than the thickness of the connecting bar so as 5 to permit of a certain amount of sidewise movement while the pivoting pin allows the valve stem a certain amount of lateral movement in order that the valve may adjust itself to its seat and in order to prevent the 10 valve stem from swinging too far the upper end of the connecting bar is provided with horns 23' which coact with the stem above its bifurcated end.

The lower end of the connecting bar 15 carries a pin 24 projecting from both of its faces for registration with the horizontal slot 25 in the free end of the diaphragm lever 26 when said connecting bar is inserted in the vertical slot 27 in said free end 20 of the diaphragm lever.

The diaphragm lever is mounted intermediate its ends upon a shaft 28 the ends of which are socketed in screws 29 threaded through the walls of the governor body or 25 casing while the opposite end of said diaphragm lever is pivoted as at 30 to the hanger 31 carried by the plate 32. Between the plate 32 and another larger one 33 which is attached to the plate 32 is mounted a dia- 30 phragm 34 the edges of which are held between the enlargement 3 and the cover 35 by suitable fastening devices 36, here shown as bolts and nuts. The cover 35 forms another portion 37 of the diaphragm chamber and 35 has a centrally located boss 38 into which is threaded an adjusting screw 39 the inner end engaging one end of a spring 40 while the other end of said spring rests upon the plate 33 to provide a certain amount of pres- 40 sure upon the diaphragm in addition to that supplied by the weights 32 and 33.

The cover 35 has a duct 41 to form a communication between that portion 37 of the diaphragm chamber above the diaphragm 45 and a hole 42 leading to the waste chamber 43 from which leads a waste outlet 44 for connection with a suitable conduit such as a pipe which may lead to some distant point such as for instance outside of a building in 50 which the governor is located.

In a hole 45 between that portion of the diaphragm chamber below the diaphragm and the waste chamber 43 is located a tube 46 of any desirable length and open at both 55 ends said tube passing through and beyond the waste chamber. Surrounding the outer end of this tube is a fluid container or barrel 47 of greater diameter than the tube so as to form a space thereabout and this fluid 60 container or barrel is threaded into an opening 48 leading to the waste chamber 43. If found desirable the fluid container or barrel may have an outlet 49 normally closed by a plug 50.

65 This fluid container is adapted to hold oil,

glycerine, mercury or other suitable substance so as to prevent leakage of gas through the waste pipe under ordinary conditions but will permit said gas to blow out through the waste outlet should the pressure within the governor become too great and if by any chance the diaphragm should become impaired by any leakage of gas above said diaphragm such gas will pass through the duct 41 and hole 42 into the waste chamber 43 and then out through the waste outlet 44.

From the foregoing description it will be seen that as the gas enters the inlet 11 it will pass through the channel 12 into the valve 80 chamber 13 and then through the hole 16 into the lever chamber and the lower portion of the diaphragm chamber. The flow of this gas under high pressure into the valve chamber 13, to some extent, acts upon the valve 18 85 and tends to force it toward its seat while that portion which has entered the lever dia- phragm chambers will tend to raise the dia- phragm against the action of the weighted plates 32 and 33 and the spring 40 thereby 90 gradually moving the valve toward its seat so as to regulate the flow of gas into the dia- phragm and lever chambers and thus govern the pressure of the gas which may be drawn off through the discharge outlet 15. The 95 amount of pressure may be regulated by changing the tension of the spring 40 through the medium of the adjusting screw 39 and may also be further regulated by adjusting the valve 18 relative to its seat upon the valve stem 21.

In some devices of this character it has always been very difficult and impractical and in most cases impossible to clean the valve should the same become clogged with 105 foreign matter often passing through the service pipes and when the valve had to be repaired it was necessary to remove the governor and send it to the repair shop or factory. These disadvantages are entirely over- 110 come by the use of my invention for after the gas has been turned off between the main and governor the cap 8 can be readily removed to give access to the valve and its component parts thereby permitting the 115 valve head to be removed and cleaned after which it may be replaced or if damaged another may be readily substituted therefor.

Should it become necessary to remove the diaphragm lever, the valve stem or the connecting bar the cover 35 is removed and the socket screws 29 backed out sufficiently to release the axle 28 after which the diaphragm with its weights and lever may be readily withdrawn and the withdrawing movements 120 will disengage the connecting bar and its pin 24 from the notched end of the diaphragm lever when the valve with its component parts will be free for withdrawal through the hole 16. After the necessary repairs have 125 130

been made the parts may be again assembled by reversing the operations above described.

Of course I do not wish to be limited to the exact details of construction as herein shown as these may be varied within the limits of the appended claims without departing from the spirit of my invention.

Having thus fully described my invention, what I claim as new and useful is:—

10 1. A gas governor including a housing or casing having an inlet and outlet, a removable cap on the housing constituting a valve enclosure, a diaphragm within the housing, a lever connected to the diaphragm, 15 a valve located outside of the housing and within the cap so as to be accessible upon removal of said cap and means connecting the valve and lever.

2. A gas governor comprising in combination, a housing having a valve seat on the exterior thereof, a valve coacting with said seat, means actuated by the pressure of gas to operate said valve and removable means enclosing said valve and its seat.

25 3. In combination, a gas governor housing having a diaphragm chamber, a lever compartment, an outlet leading from the lever compartment and a hole leading to said lever compartment from the exterior 30 of the housing, a valve seat surrounding said hole, a cap detachably mounted on the housing in the region of the valve seat to form a valve chamber, the housing also having a gas inlet communicating with the 35 valve chamber, a diaphragm in the diaphragm chamber, a lever having one end connected to said diaphragm, and a valve exteriorly located relative to the housing for action with the valve seat and connected to the other end of the lever, said valve being readily accessible upon removal of the cap.

4. In combination, a gas governor housing having a diaphragm chamber, a lever compartment, an outlet leading from the lever compartment and a hole leading to said lever compartment from the exterior of the housing, a valve seat surrounding said hole, a cap detachably mounted on the 50 housing in the region of the valve seat to form a valve chamber, the housing also having a gas inlet communicating with the valve chamber, a diaphragm in the diaphragm chamber, a lever having one end connected to said diaphragm, and a valve 55 so located that its opening movement is opposed to the flow of gas, said valve being connected to the opposite end of the lever.

5. In a gas governor the combination of

a housing, a diaphragm therein, a lever connected at one end to the diaphragm and having at the other end two slots at right angles to each other, an axle on which the lever is mounted, socket screws in which the ends of the axle are mounted, a connecting bar adapted to be inserted in one of the slots in the lever, a pin carried by the bar for insertion in the other slot, a valve stem pivoted to the connecting bar and a valve having threaded connection 70 with the valve stem for adjustment thereon.

6. In combination, a gas governor housing including one portion of a diaphragm chamber, a lever compartment communicating therewith, an outlet leading from the lever compartment, a hole leading to said lever compartment from the exterior of the housing, and a waste chamber, said waste chamber having a hole leading thereto from the exterior, another hole forming a communication between the aforementioned portion of the diaphragm chamber and the waste chamber, an opening leading to the waste chamber concentric with said other hole, and a waste outlet, a cover having a recess to form the balance of the waste chamber and further provided with a duct or by-pass to form a communication between that portion of the diaphragm chamber within the cover and the first named hole, a tube open at both ends projecting through the opening and mounted in said other hole, a fluid container of greater diameter than the tube mounted in the opening and surrounding the outer end of said tube, a diaphragm within the diaphragm chamber, weighted plates connected therewith, resilient means for exerting pressure on said diaphragm, means for regulating the tension of said resilient means, a lever pivoted 90 within the lever compartment and connected at one end with the diaphragm, a connecting bar pivoted to the outer end of the lever and passing through the hole leading to the lever compartment, a valve stem pivoted to the connecting bar, a valve adjustably mounted on said stem and located exteriorly of the housing for controlling the flow of gas through the last mentioned hole, and a cap detachably mounted on the housing for enclosing said valve and forming a chamber which acts as a portion of the gas inlet, the balance of said gas inlet being formed in the housing.

In testimony whereof, I have hereunto affixed my signature.

FRED P. SMITH.
